UNITED STATES PATENT OFFICE.

JOHN K. HARRIS, OF ALLENSTVILLE, INDIANA.

IMPROVED PRESS FOR PRESSING HAY, COTTON, &c.

Specification forming part of Letters Patent No. 33,083, dated August 20, 1861.

To all whom it may concern:

Be it known that I, JOHN K. HARRIS, of Allensville, in the county of Switzerland and State of Indiana, have invented a new and Improved Press for Compressing Hay, Cotton, and other Articles or Substances for Baling; and I do hereby declare that the following is a full, clear, and exact description of the same, reference being had to the annexed drawings, making a part of this specification, in which—

Figure 1 is a side sectional view of my invention; Fig. 2, a front view of the same; Fig. 3 is a plan sectional view of the same; Fig. 4, a detached perspective view of a part of the feed-gate; Fig. 5, a detached horizontal section of one of the uprights, taken in the line x - x , Fig. 1; Fig. 6, a detached perspective view of a portion of the follower and beater; Fig. 7, a detached perspective view of a portion of the driving-pulley and its slide.

Similar letters of reference indicate corresponding parts in the several figures.

This invention relates to certain improvements on a press for which Letters Patent were granted to Samuel Hewitt, December 30, 1843. The press of Hewitt's was provided with a beater, so arranged and applied as to fill the press-box or compact therein the substance to be pressed, thereby avoiding the necessity of an attendant to fill the box by the comparatively slow process of trampling. The beater of Hewitt's press was operated automatically, but simultaneously with the descent of a follower, which was actuated by a single screw. This arrangement is attended with some disadvantages. Each fall of the "beater" on the loose substance thrown in at the filling-door has to force the successive layers of hay condensed or compacted by its previous action until it overtakes the gradually-descending follower, and then the whole mass during the pressing operation is pressed back again by the action of the follower, the bale being completed at the top of the box. This involves unnecessary surface-friction, and in some degree arrests the condensing or compacting power of the beater itself. Experience has also detected another serious objection to the single screw applied to the center of the follower, and that is when one end of the bale is compacted a trifle harder than the other—a contingency of frequent occurrence—the fol-

lower inclines to tilt or bind in the press-box, causing great friction, and not unfrequently breaking the screw or nut through which the screw works. The press of Hewitt's was also cumbersome, or could not be made portable. It required to be suspended in a large or high building, with heavy timbers for its support, and with a "pit" or basement-story for the team to work it.

The object of the within-described invention is to obviate these difficulties and still retain all the advantages of the original press, or, rather, of the beater, which formed its distinctive feature; and to this end I employ two screws, and so arrange the beater therewith that it may perform a double function—to wit, that of a beater and of a follower. I also employ certain other parts, hereinafter described, for the purpose of automatically opening and closing the feeding-door.

To enable those skilled in the art to fully understand and construct my invention, I will proceed to describe it.

A represents a horizontal rectangular frame, at one end of which two uprights, B B, are placed, the upper ends of which are connected by traverse-bars a a , between which a pulley, C, is placed.

At the lower part of the uprights B B the press-box D is placed. This press-box may be formed by securing plank to the front and back sides of the uprights.

At the lower part of the press-box D there are doors E E, one at the front and the other at the back side. These doors are connected at one end to the press-box by hinges a , and the opposite ends, when closed, are connected by a clamp, F, constructed and arranged in any proper way.

At the upper part of the press-box, at its front side, there is a feed-door, F', the lower end of which is connected by a joint to the press-box. This door opens and closes on guide-plates b b , which retain it in proper position. The door F' is retained in a closed state by hooks c c , which are attached by pivots d , one to each upright B, and catch over the top bar or rail, e, of the door.

In the back of the top bar or rail, e, of the door a longitudinal groove is made, in which a rod, f, is fitted. (See Fig. 4.) This rod has a lever, g, attached to it at one end, said le-

ver being provided with a curved arm, *h*, which extends upward in front of bar *e*, and at the opposite end of the rod *f* there is a similar curved arm, *i*. These arms *h i*; when the door *F* is closed, are directly underneath the hooks *c c*.

To the lower end of the lever *g* a cord, *j*, is attached. One part of this cord extends upward around a pulley, *j'*, and is connected to a lever, *k*, which is of bent form, and projects inward at the inner side of its bearing or fulcrum, so as to be parallel with its outer part. This lever *k* is secured to one of the uprights *B* at its upper part. The other part of the cord *j* extends down and passes through a guide-hole, *l*, in the base *l'* of the press-box, and has its end attached to a bent lever, *G*, on the horizontal frame *A*.

In each upright *B* a vertical slot, *m*, is made, as shown in Fig. 1, and in each upright a vertical screw-shaft, *H*, is fitted, the upper parts of the screw-shafts being in the slots *m*. The screw-shafts project through the base *l'* of the press-box, and have each a toothed wheel, *n*, around which an endless chain, *I*, passes, said chain also passing around a larger toothed wheel, *J*, which is placed horizontally on the frame *A*, and has a concentric pulley, *K*, attached, the periphery of which is grooved to receive a segment-slide, *L*, to which a rope, *M*, is attached, said rope passing through a guide in the base *l'* of the press-box, and extending upward to the top of the uprights, and over the pulley *C*, and thence downward, the end of the rope being attached to a vertical slide bar, *N*, which is fitted in the upright *o*, of a follower, *O*, which works between the uprights *B B*, and within the press-box *D*. (See Fig. 2.) The slide bar *N* has an arm or lever, *P*, projecting from it at each side, said levers having their inner ends attached to the bar, *N*, by a common fulcrum-pin, *p*. The outer ends of the levers *P P* are connected to bars *Q Q*, which are secured one in each side of the follower by fulcrum-pins *q q*. (See Fig. 2.) The upper ends of the bars *Q* have each two laterally-projecting ears, *r r*, attached, as shown in Fig. 6.

On each screw-shaft *H* a nut, *S*, is fitted. These nuts work in the slots *m*, and each nut has a recess made in its inner side to receive a guide-bar, *s*, said bars being secured to the inner sides of the uprights in line with the slots *m*, and preventing the nuts from turning therein or bearing against the sides of slots *m*, under the action of the screw-shafts. (See Fig. 5.)

In the pulley *K* there is fitted a vertical slide-catch, *t*, which is allowed to work freely up and down therein. This catch may be described as being in the form of a staple, one leg being longer than the other and projecting below the pulley, while the shorter leg projects down over the side of the pulley, and acts against a projection, *n'*, on the slide *L* of pulley *K*. (See more particularly Fig. 7.)

U is a stop which is attached to the frame

A in a radial position with pulley *K*, the inner end of the stop being not quite in contact with the periphery of pulley *K*. (See Fig. 3.)

To the under side of wheel *J* a pin, *v*, is attached, the use of which will be presently shown.

V is a sweep which is attached to pulley *K*.

The operation is as follows: At the commencement of the work the nuts *S S* are at the bottoms of the slots *m m* in the uprights *B B*. The draft-animal is attached to the sweep *V*, and the latter turned in the direction indicated by arrow 1, Fig. 3. The pulley *K* and wheel *J* are, of course, rotated in the same direction, and the chain *I* communicates motion to the screw-shafts *H H*, which, as they turn, cause the nuts *S* to travel upward in the slots *m m*. As the pulley *K* rotates, the short leg of the catch *t* will catch against a projection, *n'*, of the slide *L* and cause the rope *M* to be wound on the pulley *K* until the long leg of the catch comes in contact with a projection, *b'*, on the frame *A*, beneath the pulley *K*, which projection throws up the catch and releases the projection *n'* of the slide *L* from the shorter leg of the catch. When the rope *M* is wound on the pulley *K*, the follower *O* is raised, and when the slide *L* is released from the catch *t*, the rope is disconnected from the pulley *K*, and the follower is allowed to fall by its own gravity and drop within the press-box *D*. When the slide *L* is released, it travels around on the periphery of the pulley under the action of the descending follower until arrested by stop *U*, at which point it is ready to be acted upon by the short leg of catch *t*. Thus it will be seen that by a continuous rotation of pulley *K* the follower *O* is operated. This follower *O*, while thus working, performs the function of a beater, and compacts the substance to be pressed within the box *D*. Each time the follower *O* nearly reaches its culminating-point it strikes the inner arm of lever *k*, and actuates the cord *j* and draws up and closes the feed-door *F*, and immediately after each descent of the follower and beater the pin *v* of the pulley *K* will strike the bent lever *G*, and the lower part of the cord *j* will be actuated and the lever *g* and shaft *f* turned, so as to cause the bent arms *h i* to throw up the hooks *c c* and allow the door *F* to drop and open by its own gravity, the substance to be pressed being thrown into the press-box *D* each time the follower and beater passes above the door. When the press-box *D* is supplied with a requisite quantity of the material to be compressed, the nuts *S* will have reached an elevated position in the slots *m m*, and the sweep *v* is then turned in an opposite direction. When the follower and beater *O* strike the substance or material in the box *D*, the slide-bar *N*, being released from the pull of rope *M*, will by its own gravity force outward the bars *Q Q*, through the medium of the arms or levers *P P*, and the ears *r r* of the bars *Q* will pass under the nuts *S* and, at each side of the bars *s*. The nuts, as they descend under the re-

verse motion of the screws, will force down the follower and beater and compress the substance in the box D, the function of a follower being performed in the latter operation. The substance is compressed at the bottom of the box D, and the bale removed from the lower part. The motion of the pulley K is then reversed, and the operation repeated.

I do not claim the employment or use of a beater in connection with a follower operated by a screw or other device for compressing substances for baling, for such device has been used; but

I do claim as new and desire to secure by Letters Patent—

1. The follower and beater O, in connection with the screws H H and hoisting-rope M, or analogous devices, so arranged and applied as to admit of the follower and beater performing the filling or packing, and also the compressing operation, substantially as herein set forth.

2. The means, substantially as herein shown and described, for operating or opening and

closing automatically the feed-door F, to wit: the cord j, connected to the lever g, which is attached to the rod f in the door, the curved arms h i, and hooks c c, the cord j, passing over suitable pulleys j' j", and connected at its ends to levers k G, which are actuated, respectively, by the follower and beater O and pin v of wheel J.

3. The pulley K, wheels J n n, and endless chain I, in combination with the slide L, catch t, stop U, and projection b^x, for operating the screw-shafts H H and rope M, substantially as described.

4. The guide-bars s s, attached to the inner sides of the uprights B B, and fitted in notches or recesses in the inner sides of the nuts S S, to serve as guides for the latter, and also as guides to the bars Q Q of the follower, the ears r r of which are at each side of the bars s s.
